Primary Examiner — Ralf T Seifert(74) *Attorney, Agent, or Firm* — Perkins Coie LLP(57) **CLAIM**

The ornamental design for a web adjuster, as shown and described.

DESCRIPTION

FIG. 1 is a rear isometric view of the web adjuster showing an embodiment of our new design;
 FIG. 2 is a front isometric view thereof;
 FIG. 3 is a top plan view thereof;
 FIG. 4 is a bottom plan view thereof;
 FIG. 5 is a rear elevation view thereof;
 FIG. 6 is a front elevation view thereof;
 FIG. 7 is a right elevation view thereof; and,
 FIG. 8 is a left elevation view thereof.

The broken lines in the Figures show portions of the web adjuster which form no part of the claimed design.
